UNITED STATES PATENT OFFICE.

THOMAS G. HAWKES, OF CORNING, NEW YORK.

DESIGN FOR A GLASS VESSEL OR DISH.

SPECIFICATION forming part of Design No. 26,730, dated March 9, 1897.

Application filed February 1, 1897. Serial No. 621,573. Term of patent 14 years.

To all whom it may concern:

Be it known that I, THOMAS G. HAWKES, a citizen of the United States, and a resident of Corning, in the county of Steuben and State of New York, have invented and produced a new and original Design for a Glass Vessel or Dish, of which the following is a specification, reference being had to the accompanying drawings, forming part thereof, in which—

5 Figure I is a bottom view of a glass bowl, showing my design. Fig. II is an axial section thereof.

The leading features of my design consist of a large central figure having radial scalloped arms, a large quadrangular figure having a central rosette located at the end of each arm, and a radial series of quadrangular figures each having a central rosette and extending between the arms, thus forming 15 what I call the "Nelson" design.

A large central figure having elongated and spreading radial arms extends over the main portion of the vessel or dish. Between these arms, and gradually increasing in size from the center to the circumference, are a series 25 of quadrangular figures each having a central rosette, and at the ends of the arms are intermediate quadrangular figures having a rosette.

Having thus described my invention, the 30 following is what I claim as new therein and desire to secure by Design Letters Patent:

The design for a glass vessel or dish; substantially as herein shown and described.

THOMAS G. HAWKES.
